UNITED STATES PATENT OFFICE.

ALEXANDER CHURCHWARD, OF NEW YORK, N. Y., ASSIGNOR TO GENERAL ELECTRIC COMPANY, A CORPORATION OF NEW YORK.

POLE-PIECE.

No. 796,702.

Specification of Letters Patent.

Patented Aug. 8, 1905.

Application filed October 26, 1902. Serial No. 128,694.

To all whom it may concern:

Be it known that I, ALEXANDER CHURCHWARD, a citizen of the United States, residing at New York, county of New York, State of New York, have invented certain new and useful Improvements in Pole-Pieces, of which the following is a specification.

My invention relates to dynamo-electric machines, and has for its object the production of means whereby the sparking output of such machines may be controlled without adjustment of the brushes about the commutator.

It has been recognized for some time that the sparking action of the brush was due to the change in the position of the neutral axis caused by the variation of the loads upon field-poles having a non-uniform distribution of magnetic lines of force in their working faces. The leading tips of the common pole-pieces are worked up to the point of magnetic saturation under ordinary loads, while the flux from the remainder of the pole-faces decreases in intensity from that point to the opposite tip, where it is practically zero, so that the center of the effective area is near the leading tip. When increased load is thrown upon the poles, the flux from the unsaturated portion of the pole-face is increased so that the center of effective area is moved back farther away from the leading tip. Attempts have been made heretofore to bring about a uniform distribution of the magnetic lines of force in the working surfaces of field-poles; but so far as I am aware these attempts have not been satisfactory.

My invention consists in providing a field-pole with means for concentrating the lines of magnetic force near the working face of the pole, so that at ordinary loads the whole pole-piece near its working face will be worked at the upper part of the curve of saturation, and when an overload is thrown upon the machine the additional magnetic lines of force resulting therefrom will distribute themselves uniformly over the whole working face of the pole, and as a consequence the effective center of the total flux will not be changed.

In carrying out my invention I provide transverse holes in the ends of the field-poles with their bases near the working faces of the poles. I also contemplate using copper end plates on the poles and connecting them by bars which shall pass through the holes in

the pole-pieces in order to neutralize cross-currents.

My invention will be readily understood upon reference to the accompanying drawings, forming a part of the specification and showing an embodiment of my invention, in which—

Figure 1 is a diagrammatic view of a dynamo-electric machine with two field-poles in elevation and one in longitudinal section. Fig. 2 is a bottom plan of a pole-piece shown in Fig. 1, and Fig. 3 is a longitudinal section of a modified form of pole-piece.

The field-poles shown in the drawings are made up of laminae punched from sheet-iron, with a tip of each cut off, as indicated at 1 and 2, and with a series of triangular holes 3 punched in the working end. The respective laminae are assembled so that their cut tips will alternate, as is customary. The holes 3 have their bases parallel with the working face of the pole and are so located with respect to each other and to the pole-face that the remaining metal is most contracted very near the working face. As a consequence of this arrangement the flux under ordinary loads is gradually concentrated from the vertex of the triangular holes 3 until it reaches the plane of their bases, where it permeates the iron for a very short distance at a comparatively high degree of saturation. After passing the plane of their bases it is free to spread out again and distribute itself in the metal between the bases of the holes and the working end of the pole. Care should be taken, however, that this metal so remaining should not be sufficient to allow a cross flow of the flux toward the leading tip of the pole.

As shown in Figs. 1 and 2, the pole-piece is provided with a projecting shoulder 4, which serves to support the field-spool 5. The end plates 6 of the pole-piece are of copper or other good conducting material and are connected with each other and held in position by conducting-rods 7, which pass freely through the holes 3. The arrangement shown in Fig. 3 is the same except that the end plates extend the full length of the pole-piece, while in the first form the end plates cover only that part of the pole-piece visible beneath the inner end of the field-coils.

It is apparent that the shape of the transverse holes 3 need not necessarily be triangular, for any shape or size of hole which will

make the concentration of the magnetic lines of force greatest near the pole-face is adapted to carry out my invention.

What I claim as new, and desire to secure by Letters Patent of the United States, is—

1. In a dynamo-electric machine, a pole-piece having a triangular slot formed in it, said slot being located near the face of the pole and drawn parallel to the axis of the armature of the machine, with one flat side of the slot substantially parallel to and closely adjacent to the pole-piece.

2. A magnetic pole having a hole formed in it, said hole having one side parallel to the face of the pole, the cross-sectional area of the hole beyond said side diminishing with the distance from the pole-face.

3. A magnetic pole having therein one or more triangular holes with one side parallel and in proximity to its working face.

4. A magnetic pole having therein triangular holes in proximity to its working face.

5. A magnetic pole having therein triangular holes with one side parallel with and in proximity to its working face.

6. A magnetic pole having triangular holes in proximity to its working face, and means for neutralizing cross-currents.

In witness whereof I have hereunto set my hand this 22d day of October, 1902.

ALEXANDER CHURCHWARD.
